US00D617738S

(12) **United States Design Patent**
Chen et al.

(10) **Patent No.:** US D617,738 S
(45) **Date of Patent:** ** Jun. 15, 2010

(54) **RECEPTACLE CONNECTOR**

(75) Inventors: **Feng Chen**, Tu-Cheng (TW); **Feng Zhu**, Tu-Cheng (TW); **Kuo-Chin Lin**, Tu-Cheng (TW)

(73) Assignee: **Cheng UEI Precision Industry Co., Ltd.**, Tu-Cheng, Taipei Hsien (TW)

(**) Term: **14 Years**

(21) Appl. No.: **29/344,651**

(22) Filed: **Oct. 1, 2009**

(51) **LOC (9) Cl.** 13-03

(52) **U.S. Cl.** D13/147

(58) **Field of Classification Search** D13/147, D13/154, 184; 439/79, 108, 607-610, 680-682, 439/686

See application file for complete search history.

(57) **CLAIM**

The ornamental design for receptacle connector, as shown and described.

DESCRIPTION

FIG. 1 is a perspective view of receptacle connector showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another perspective view of receptacle connector showing our new design.
